STACKABLE CHAIR

Everett Stacy Dukes, 247 Loma,
Long Beach, Calif. 90803

Filed Apr. 9, 1971, Ser. No. 132,929

Term of patent 14 years

Int. Cl. D6—02

U.S. Cl. D6—65

FIG.1

FIG.2

FIG.3

FIG.4

FIG.5

FIG. 1 is a three-quarter front perspective view of a stackable chair embodying my new design;

FIG. 2 is a side elevational view of said chair, with the side opposite that shown having the same appearance as the side appearing in this figure;

FIG. 3 is a rear elevational view of said chair;

FIG. 4 is a front elevational view of said chair; and

FIG. 5 is a top plan view of said chair.

I claim:

The ornamental design for a stackable chair, substantially as shown and described.
